SAFETY APPARATUS FOR SHIPWRECKED PERSONS

Luigi Ghirardi, Genoa, Italy

Application February 27, 1931, Serial No. 518,805,
and in Italy November 8, 1930

1 Claim. (Cl. 9—22)

This invention relates to improvements in life saving apparatus for use on ships and the object of the invention is the provision of an improved raft embodying such features of construction that it may be easily launched from the deck or other part of a ship and, when positioned in the water, will provide a safe and spacious life saving craft.

In the accompanying drawings an improved embodiment of the invention is illustrated.

10 Fig. 1 is a fragmentary side elevation of a ship showing the invention applied to use.

Fig. 2 is a vertical section on the line 2—2 of Fig. 1.

15 Fig. 3 is a transverse sectional view on an enlarged scale through the life saving craft.

Fig. 4 is an enlarged fragmentary side elevation of the raft showing the retaining means for one of the protecting members.

20 Fig. 5 is a perspective view of the improved raft.

Fig. 6 is a top plan view of a modified form of raft.

25 Figs. 7 and 8 are fragmentary views of different portions of a ship illustrating the various arrangements of the improved life saving raft thereon.

Fig. 9 is an elevation of a further modification of the mounting of the improved raft on board a ship.

30 Fig. 10 is an elevation partly in section of a further modification of the retaining means for the improved raft.

Referring to the drawings in detail, the numerals 50 and 51 indicate the end members of 35 the raft rotatably supporting the three buoyant cylindrical bodies 4 and 5, the body 4 being rotatably mounted at 4a between the axes 5a of the two rollers 5. Flat board-like members 1 and 2 extend between the end members 50 and are located between the cylindrical bodies 4 and 5 and constitute the floor of the raft. The space between the floor members 1 and 2 may be utilized for storage purposes and access thereto may be had through suitable openings which are normally closed by the cover plates 3.

45 Substantially T-shaped members 7 are pivotally mounted at the axes 5a of the cylindrical bodies 5. The stem portions of the members 7 at each side of the raft are connected by protecting members 50 6 which, in the position shown in Fig. 3, lie laterally of the cylindrical bodies 5a. Pivoted retaining members 8 having recesses therein to receive the arms of the members 7 are provided and lock said members 7 in adjusted position. The members 7 are adapted to be turned about their axes

5a to bring the protecting members 6 into the upright position illustrated in dotted lines in Fig. 3 and in full lines in Fig. 5.

The protecting members 6 are retained in their upright positions in which they are arranged when the raft is occupied, by means of hooks 10 pivotally mounted at 9. The outer edges of the protecting members are notched as at 6a so as to retain oars 24 with which the raft is equipped.

60 The improved raft is mounted on a ship as shown in Figs. 1 and 2 and is preferably disposed at an inclination so that, when released, it will freely roll overboard. The inclined supports for the raft are indicated in Figs. 1 and 2 at 11 and the raft is normally held in position by retaining members 12 hinged at 13 and adapted, when swung outwardly as indicated by the arrow 13' in Fig. 1, to release the raft and permit the latter to roll overboard in the direction of the arrow 14 in Fig. 2. The raft may, if desired, be compactly stored aboard a ship beneath one of the usual life boats 15 supported by means of a suitable launching arrangement indicated at 16.

65 In the modification of the invention illustrated in Fig. 6, each of the cylindrical buoyant members 4 and 5 is divided into a plurality of parts. The parts 5b of the bodies 5 are mounted to rotate so as to facilitate launching of the raft while the remaining portions 5c thereof are stationary. While the parts 4b of the center cylindrical body are rotatably mounted, the remaining portions 4c thereof are stationary. In other respects the form of raft shown in Fig. 6 is the same as that illustrated in Figs. 1 to 5.

70 According to the arrangement shown in Figs. 7 and 8, the life saving raft is normally held in a holder 21 pivotally mounted at 21a and normally disposed in the upright position illustrated in full lines. When released, the holder swings outwardly in the direction of the arrow 22 and to 75 the position indicated at 21' and the raft may freely roll outwardly in the direction of the arrow 14 into the water.

75 A further modified arrangement of the retaining device for the raft is illustrated in Fig. 9 in which the raft is normally held in position on the inclined supports 11 by means of a pin 17 which when withdrawn in the direction of the arrow 18, permits the raft to roll into the water.

80 In the modification illustrated in Fig. 10, a life boat 28 is supported from davits 29 and, when launched, moves outwardly in the direction of the arrow 30, the davits 29 moving outwardly on guides 31. Between the guides 31 the improved raft is arranged to roll on a guide 32 arranged 85

at an inclination as shown in Fig. 10. In this figure the rotatable cylindrical bodies of the raft are indicated as 4 and 5 and the raft is retained in position by stops 33. The stops 33 form arms of a shaft 34 on which is fixed a lever 36 provided at one end with a weight 35 normally tending to swing the shaft 34 in a direction to remove the stop 33 from the path of the raft. The opposite end of the lever 36 is engaged by a retaining lever 37 pivotally mounted at 38 and having an extended end 39 engaged by a retaining member 40. When the retaining member 40 is disengaged from the extended end 39 of the lever 37, the latter is released and the shaft 34 is rotated counter-clockwise under the influence of the weight 35

thereby removing the stop 33 from the path of the raft and permitting the latter to roll downwardly along the guides 32 into the water.

I claim:

A life saving raft comprising buoyant cylindrical rotatable bodies, substantially flat members interposed between said bodies, and adjustable protecting members, each protecting member being pivotally mounted on the raft and movable to positions above and below the latter, the pivotal axis of said protecting member coinciding with the axis of certain of said cylindrical bodies. 80 85
